UNITED STATES PATENT OFFICE.

GEORGE CLAUSING, OF PORTSMOUTH, OHIO, ASSIGNOR TO THE VULCAN LAST COMPANY, OF PORTSMOUTH, OHIO, A CORPORATION OF OHIO.

LAST.

Application filed April 22, 1925. Serial No. 24,992.

My invention relates to lasts and in particular to a snap back last.

It is the object of my invention to provide a last in which the parts may be simply and effectively maintained in predetermined relationship with one another and in which the last parts will be yieldingly maintained in expanded position and constantly be restored to that position when the parts 10 are permitted to freely operate.

It is the object of my invention to provide a very cheap and simple, but sturdy form of last.

Referring to the drawings:

15 Figure 1 is a side elevation of the last partially in section cut away to show the arrangement of the snap back spring and connecting link; and

20 Figure 2 is a section on the line 2—2 of Figure 1 in the direction of the arrows.

Referring to the drawings in detail, 1 is the toe part of the last having a cut away portion 2 for accommodating the spring and links. This toe part on its rear face is provided with a transverse semi-circular groove 3 in which fits a transverse partially circular projecting shoulder 4 of the heel part 5. These parts are limited in their expanded position by their respective shoulders 6 and 7 located below the socket joint. The space above the socket joint between the last parts is substantially V-shaped when in expanded position due to the fact that the faces adjacent to one another of the last parts designated 8 and 9 are disposed at an angle to one another normally to permit of the collapsing of the last parts.

25 The heel part 5 is provided with a cut away portion 10 for receiving the spring which snaps the last halves back in expanded position.

30 Transversely located in the last parts and intersecting the cut away portions 2 and 10 are anchor pins 11 and 12. These anchor pins have hooked over them an arched shaped spring 13 with hooks 14 at either end thereof. A hinge pin 15 is transversely located in the partially circular transverse shoulder 4 of the heel part. This hinge pin carries a pair of spaced toe links 16 the other ends of which are mounted on the anchor pin 11 on either side of the spring 13 serving to keep the spring in position.

35 It will be observed that the center of the hinge pin never passes a line drawn be-

tween the centers of the anchor pins 11 and 12 so that the spring 13 constantly tends to snap the parts back into expanded position.

It will be understood that I desire to comprehend within my invention such modifications as may be necessary to adapt it to varying conditions of use.

Having fully described my invention, what I claim as new and desire to secure by Letters Patent, is:

1. In a snap back last, a toe part and a heel part, a projection on one part fitting into a socket in the other part to permit the parts to rock on one another, a hinge pin located in said projection, the center of the pin being the center of the movement of the parts, a link mounted on said hinge pin connecting the part in which the pin is located with the other part, an anchor pin in the other part for supporting the link, and a bow spring mounted on said anchor pin at one end and upon a second anchor pin in the other last part at the other end, and a second anchor pin, the centers of said anchor pins being so arranged that a line drawn therebetween never passes over the center of the hinge pin.

2. In a snap back last, a toe part and a heel part, said parts being adapted to rock upon one another, a hinge pin located in one of said parts with its center on the center of movement of the parts, a pair of links mounted thereon connecting one part to the other, an anchor pin for supporting said links in the other part, an arched shaped spring adapted to clear the hinge pin hooked to the anchor pin and located between the links, and a second anchor pin in the other last part adapted to support the other end of the spring, the centers of said anchor pins being so arranged that a line drawn therebetween never passes over the center of the hinge pin.

3. In a snap back last, last parts adapted to rock one on the other, a two part jointed link connecting said parts, a yielding connecting member arranged so that its points of attachment through the last parts will not pass by the center of movement of the last parts whereby a line drawn between the centers of attachment will always be below said center of movement.

In testimony whereof, I affix my signature.

GEORGE CLAUSING.
